UNITED STATES PATENT OFFICE.

LEO F. ADT, OF TROY, NEW YORK.

DESIGN FOR A COLLAR-BUTTON.

SPECIFICATION forming part of Design No. 32,775, dated June 5, 1900.

Application filed April 13, 1900. Serial No. 12,779. Term of patent 14 years.

To all whom it may concern:

Be it known that I, LEO F. ADT, a citizen of the United States, residing at Troy, in the county of Rensselaer and State of New York, have invented and produced a new and original Design for Collar-Buttons; and I do hereby declare the following to be a full, clear, and exact description of the same, reference being had to the accompanying drawings, forming a part thereof.

Figure 1 is a side elevation of a collar-button, showing my new design. Fig. 2 is a vertical sectional view of the same.

As shown in the drawings, the leading or material features of my design consist of a circular base A, having a shank *a*, extending outward from the central portion of said base

in curved lines and terminating in a head B', having curved transverse outlines considerably smaller in diameter than the base A, and a head B, substantially similar in dimensions and outlines to the head B' and connected with said head B' by means of a shank *b*, considerably shorter in length than the shank *a*.

What I claim is—

The design for a collar - button, substantially as herein shown and described.

In testimony whereof I affix my signature in presence of two witnesses.

LEO F. ADT.
